UNITED STATES PATENT OFFICE.

VICTOR BRISBOIS, OF ELMHURST, NEW YORK.

DESIGN FOR BOWL OR SIMILAR ARTICLE.

Application filed June 27, 1923. Serial No. 6,596. Term of patent 3½ years.

To all whom it may concern:

Be it known that I, VICTOR BRISBOIS, a citizen of the United States, residing at Elmhurst, in the county of Queens and State of New York, have invented a certain new, original, and ornamental Design for Bowl or Similar Article, of which the following is a specification, reference being had to the accompanying drawing, forming part thereof.

embodying my new design. Only a section of the ornamentation is shown in the drawing, the balance being a repetition of the ornamentation illustrated.

I claim:

The ornamental design for bowl or similar article, as shown.

VICTOR BRISBOIS.
